UNITED STATES PATENT OFFICE.

GEORGE H. BURROWS, OF SOMERVILLE, ASSIGNOR TO HIMSELF AND
ELLERY R. MERRIAM, OF BOSTON, MASSACHUSETTS.

SMOKE AND SPARK CONSUMER.

SPECIFICATION forming part of Letters Patent No. 248,019, dated October 11, 1881.

Application filed January 26, 1881. (Model.)

To all whom it may concern:

Be it known that I, GEORGE H. BURROWS, of Somerville, in the county of Middlesex and State of Massachusetts, have invented a new and useful Improvement in Smoke and Spark Consumers, of which the following is a full, clear, and exact description.

The invention consists in placing a wire plug in and causing it to project from the flue of a boiler, furnace, or heater into the combustion-chamber for the purpose of consuming the smoke and other light products of combustion, as hereinafter described.

In the accompanying drawings my invention is shown as applied in connection with boiler-flues.

Figure 1 is a sectional side elevation of one boiler-tube, and Fig. 2 is a transverse section of the same.

Similar letters of reference indicate corresponding parts.

A is the tube-sheet of a boiler; B, the tube secured therein, and C a space over the fire.

D is the smoke-consumer, consisting of a plug made up of wire in spiral coils and inserted in the end of tube B. The plug D is of a

diameter to fit tightly in the tube, and is made hollow with an enlarged head or end, d, of conical form, that projects from the end of the tube. This coiled-wire plug allows the products of combustion to pass freely, and receiving heat therefrom becomes heated sufficiently to burn up the unconsumed carbon. I prefer to use copper wire, for the reason that it is more durable under the high heat to which the metal is subjected. The device in this form is very efficient and acts without checking the draft. The enlarged head increases the surface of metal to be heated, and gives free exit at all sides.

Having thus described my invention, I claim as new and desire to secure by Letters Patent—

In combination with the flue of a boiler, furnace, or heater, a mass of wire arranged in and to project from a flue into the combustion-chamber, substantially as and for the purpose specified.

GEORGE H. BURROWS. [L.S.]
